O. P. TALLEY.
GAS GENERATOR AND BURNER.

No. 592,102.

Patented Oct. 19, 1897.

UNITED STATES PATENT OFFICE.

ORRIN P. TALLEY, OF CHICAGO, ILLINOIS, ASSIGNOR OF TWO-THIRDS TO
HENRY T. SPIVEY AND ROBERT B. SPIVEY, OF SAME PLACE.

GAS GENERATOR AND BURNER.

SPECIFICATION forming part of Letters Patent No. 592,102, dated October 19, 1897.

Application filed May 19, 1897. Serial No. 637,303. (No model.)

To all whom it may concern.

Be it known that I, ORRIN P. TALLEY, a citizen of the United States, residing at Chicago, in the county of Cook and State of Illinois, have invented certain new and useful Improvements in Gas Generators and Burners; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to that class of vapor-burners which comprise a plate corresponding in size and form to an ordinary stove-plate and adapted to fit within a stove-hole, and in which a burner is located below the plate and inclosed by a casing having a lateral aperture, and which includes also a vaporizing-chamber.

The objects of the invention are to provide a simple, cheap, and durable construction; to provide means for preventing the discharge of any liquid which may find its way to the burner from the orifices thereof; to provide means for easily cleaning and repairing the burner; to provide for changing the direction of discharge of the flame from the inclosing shell, and to provide means for removing any accumulation of carbon from the under surface of the plate. These several objects are attained in the construction hereinafter set forth, and illustrated in the accompanying drawings, in which—

Figure 1 is a detail plan view of the top of a cook-stove with my improved generator and burner applied. Fig. 2 is a side elevation of the generator and burner, portions of the top of the stove being shown in section. Fig. 3 is an inverted plan section on the line 3 3 of Fig. 2. Fig. 4 is a vertical section on the line 4 4 of Fig. 2. Fig. 5 is a detail section of the burner, taken on line 5 5 of Fig. 4. Fig. 6 is a detail elevation of the inner portion of the burner, the outer portion being removed. Fig. 7 is a sectional view on the line 7 7 of Fig. 5. Fig. 8 is a detail longitudinal section of a modified form of burner. Fig. 9 is a sectional view on the line 9 9 of Fig. 8. Fig. 10

is a detail section on the line 10 10 of Fig. 4. Fig. 11 is a detail elevation, partly in section, of a tool for manipulating movable parts of the device and showing its application to the 55 spindle for carrying the burner-inclosing shell; and Fig. 12 is a detail plan of the upper end of such spindle.

The plate A is of the general form of an ordinary stove-plate and is adapted to fit 60 within one of the holes of a cook-stove, as X. It is thicker than an ordinary stove-plate and has a chamber a, which is substantially co-extensive with its area.

The novelty of the device resides in part in 65 the casting of the plate integrally, the former practice having been to form a chambered plate of two sections, secured together by riveting or otherwise. Such devices have proved unsuccessful, for the reason that the expansion and contraction loosens the joint, how- 70 ever made.

An induction-pipe B, leading from any suitable fluid-receptacle, enters the chamber of the plate near one side, and a burner-tube 75 C leads from the chamber near the opposite side of the plate, passing through its bottom and being bent at a right angle, so that its body portion assumes a horizontal position. A burner D is attached to the end of the tube 80 C, and is cylindrical in form, and provided with two longitudinal slots d' d', diametrically disposed, and located on a horizontal plane. The end of the burner D is closed, except as to a slot d on its horizontal radii. The end c 85 of the tube C is open and abuts against the inner end of the burner D, and the sides of the pipe are cut away, so as to form apertures registering with the slots d'. These apertures may be made so large that only a pair of light 90 bars c' remain to support the outer end c of the pipe, which assumes the form of an annulus. The burner D being cylindrical in form and its discharge-orifices being upon its horizontal radii, a chamber is provided below 95 these orifices which will receive any of the fuel which may escape from the generating-chamber in liquid form, and hold it until it is vaporized by the intense heat of the burner, thereby preventing the discharge from the 100 burner-orifices of any liquid fuel.

The volatilization of the liquid held by this

chamber of the burner will cause a slight in-
erustation of the interior of the burner which
in time might clog the orifices. By rotating
the burner D this residuum is scraped off by
5 the bars c' . The burner D is preferably se-
cured to the tube C by screw-threads, as
shown.

If desired, the end of the tube C may be
cut off, so that it enters the burner D' only a
10 sufficient distance to afford proper support
therefor, and the outer end of the burner may
be open, its bore being provided with an in-
ternal screw-thread to which a plug E is
adapted. This plug is of sufficient length to
15 reach to the inner end of the burner and is
apertured from its inner end, and its sides
are cut away to form suitable apertures to
register with the lateral burner-slots d' , leaving
20 the bars e' for carrying the inner annular
end e of the plug. The plug E has its outer
end slotted, as shown at d , to form a burner-
orifice. This form of burner provides the
25 same recess or chamber for holding the li-
quid, and is cleaned in the same manner as the
burner previously described.

A draft-aperture F is formed through the
plate A directly over the burner, and is of
sufficient size to provide an ample quantity
30 of air for perfect combustion. A draft-regu-
lator in the form of a plate G is pivotally se-
cured to the upper surface of the plate A, as
shown at g' , and is adapted to swing over the
35 draft-aperture F.

Inasmuch as some air is always required,
35 and as a careless user might sometimes igno-
rantly or unintentionally entirely close the
draft, I provide the plate G with feet g g , so
as to elevate it slightly from the surface of
the plate A.

40 A bowl-shaped shell or casing H is located
below the plate A, so as to inclose the burner,
and has a lateral aperture h to provide for
the emission of the flame. In order to adapt
the device for the heating of all or any por-
45 tion of the top of the stove, I attach the shell
H by means of a spindle K, projecting cen-
trally through the plate A, and being rotatable
therin, and being fixed in the bottom of
the shell H, and prevented from rotation rela-
50 tively thereto by means of a lateral lug k .
The edges of the shell H make a compara-
tively close fit with the bottom of the plate
A, but do not bind against it, so that the shell
is free to turn with the spindle. The upper
55 end of the spindle projects through the up-
per surface of the plate A, and is adapted to
receive a wrench M, having radial lugs k' , or
being of any suitable angular form. One of
the lugs for receiving the wrench may be pro-
60 longed, as shown at k^2 , to serve as an indicat-
ing-finger, this finger being directed toward
the aperture h of the shell H, so that the po-
sition of this aperture may be known without
removing the device from its position on the
65 stove. By the use of the wrench M the shell

be discharged under either of the adjacent
stove-covers.

The handle of the wrench M may be flat-
tened, as shown at m , and may be provided
also with lateral arms m' , flattened at their
ends, whereby a convenient tool is provided
for turning and removing the burner, and
also for cleaning its lateral orifices without
removing.

75 A finger O is secured to the inner surface
of the shell H, near one of its edges, and pro-
jects inwardly toward its axis, and is adapted
to sweep the lower surface of the plate A as
the shell H is oscillated, thereby removing
80 any carbon which may have collected.

While I prefer to make the burner cylin-
drical in form for convenience in putting the
parts together and in repairing, as well as to
facilitate cleaning, I do not desire to be lim-
ited to this construction, for the reason that
85 any burner having a chamber below its dis-
charge-orifice for the purpose of receiving and
holding liquid which may enter the burner
will come within the scope of my invention.

90 I claim as my invention—

1. In a vapor-burner the combination with
a chambered generating-plate and a burner
below such plate and in communication with
its chamber, and a rotatable casing attached
95 to the under side of the plate and inclosing
the burner and having a lateral opening.

2. The combination with a cylindrical va-
por-burner having its discharge-orifices above
its lower side, of a relatively rotatable mem-
ber within the burner and having a rib longi-
tudinal as to the burner and in frictional con-
tact with the inner surface thereof.

3. In a burner the combination with a tube
having an open end and lateral apertures, of
a cap having its closed end transversely
slotted and being adapted to fit upon the end
100 of the tube to cover its lateral apertures and
having longitudinal slots for the purpose
specified.

4. The combination with a vapor-generator,
and burner below and in communication with
the generator, of a rotatable spindle extend-
ing downwardly through the generator and
controllable from above, and a laterally-ap-
115 pertured casing inclosing the burner and car-
ried by and rotatable with the spindle.

5. In a vapor generator and burner the
combination with a plate having a generating-
chamber, a burner below the plate and in
120 communication with its chamber, a rotatable
spindle extending downwardly through the
center of the plate, a case for inclosing the
burner and having a lateral aperture, such
case being carried by and rotatable with the
125 spindle.

6. In a vapor generator and burner the
combination with a plate having a generating-
chamber, a burner below the plate and in
communication with its chamber, a rotatable
spindle extending downwardly through the
130 center of the plate and having its upper end

adapted to receive a wrench, a case for inclosing the burner and having a lateral aperture, such case being carried by and rotatable with the spindle.

5 7. The combination with a generating plate, a burner below the plate and a rotatable case for inclosing the burner, of a finger secured to the case and projecting inwardly toward its axis and being adapted to 10 sweep the bottom of the plate.

8. In a burner the combination with a tube

having lateral apertures, of a cap adapted to fit upon the end of the tube to cover its lateral apertures and having longitudinal slots for the purpose specified.

15 In testimony whereof I affix my signature in presence of two witnesses.

ORRIN P. TALLEY.
